UNITED STATES PATENT OFFICE

154,922

DESIGN FOR A HOLDER FOR UPPER BOWL OF VACUUM COFFEE BREWERS

John W. Haffner, Culver City, Calif.

Application September 13, 1947, Serial No. 141,386

Term of patent 14 years

(Cl. D44—26)

To all whom it may concern:

Be it known that I, John W. Haffner, a citizen of the United States of America and a resident of the city of Culver City, in the county of Los Angeles and State of California, have invented a new, original, and ornamental Design for Holder for Upper Bowl of Vacuum Coffee Brewers, of which the following is a specification, reference being had to the accompanying drawings, forming part thereof.

In the drawings:

I claim:

The ornamental design for a holder for upper bowl of vacuum coffee brewers, substantially as shown.

JOHN W. HAFFNER.
